UNITED STATES PATENT OFFICE.

NICHOLAS S. VEDDER AND FRANCIS RITCHIE, OF TROY, NEW YORK,
ASSIGNORS TO NICHOLAS S. VEDDER, OF SAME PLACE.

DESIGN FOR A COOKING-STOVE.

Specification forming part of Design No. 6,313, dated December 17, 1872.

To all whom it may concern:

Be it known that we, NICHOLAS S. VEDDER and FRANCIS RITCHIE, each of the city of Troy, in the county of Rensselaer and State of New York, have jointly invented and produced a new and original Design for Cook-Stoves, of which the following is a specification, reference being had to the accompanying wood cut or engraving of a stove, which embodies our said design.

One part of our invention consists of the compound ornament A, shaped and arranged on a door or panel of a stove, substantially as represented in the aforesaid engraving. Another part consists of the ornament or ornaments B, shaped and arranged on a door or doors, or panel or panels, or leg or legs, of a stove or range, substantially as shown in the aforesaid wood-cut. Another part consists of the compound ornamented border molding or moldings C, shaped and arranged along the edge or edges of a door or doors, or panel or panels, of a stove, substantially as represented in the engraving. Another part consists of the combination of the ornamented border molding or moldings C and panel ornament or ornaments A or B, as represented in the aforesaid cut.

Another part consists of the design for the combined bottom plate D, side plate E, hearth-plate F, and top plate G, as distinguished by the particular moldings *h* along the edges of the plates D, F, and G, and the particular form of the side plate E with the moldings *i* and *j* thereon, all shaped and arranged together, as shown in the aforesaid engraving.

What we claim as our invention is—

1. The ornament A, shaped and arranged as herein described.
2. The ornament or ornaments B, shaped and arranged as herein set forth.
3. The compound ornamented border molding or moldings C, shaped and arranged as herein set forth.
4. The combination of the border molding or moldings C and panel ornament or ornaments A or B, as herein described.
5. The design for the combined bottom, side, hearth, and top plates D, E, F, and G, as shown and described.

NICHOLAS S. VEDDER.
FRANCIS RITCHIE.
